UNITED STATES PATENT OFFICE.

CHARLES G. BRIGHAM AND WILLIAM M. HAMILTON, OF TOLEDO, OHIO; SAID HAMILTON ASSIGNOR TO SAID BRIGHAM.

SECTIONAL BUILDING.

1,366,888.

Specification of Letters Patent. Patented Jan. 25, 1921.

Application filed May 19, 1919. Serial No. 298,109.

To all whom it may concern:

Be it known that we, CHARLES G. BRIGHAM and WILLIAM M. HAMILTON, citizens of the United States of America, and residing at Toledo, Lucas county, Ohio, have invented new and useful Sectional Buildings, of which the following is a specification.

This invention relates to building structures.

This invention has utility when incorporated in sectional or portable wooden buildings, having special advantages in features of roof assembly and construction.

15 Referring to the drawings:—

Figure 1 is a perspective view of a structure embodying the invention, being designed as a garage;

Fig. 2 is a fragmentary view of a side corner and its adjacent front battlement unit from the inside;

Fig. 3 is an elevation from the inner side of a front battlement unit;

Fig. 4 is a vertical section of the structure of Fig. 1;

Fig. 5 is a section of the front battlement unit on line V—V Fig. 2;

Fig. 6 is an enlarged detail view showing the assembly facilitating feature of flaring bolt hole; and

Fig. 7 is a bottom plan view of a roof section.

The building as herein disclosed embodies side or vertical sections 1, 2, and front sections 3 in the instance of garage structures, carrying doors 4. These vertical sections 1, 2, 3, assemble to provide in a common plane the top plates 5 and 6. Battlement units for the front and two sides are provided to rest upon these top sills of the sides and provide exterior decoration and also on the one side a support for the inclined roof downward toward the fourth or open side at the rear.

45 The front battlement unit comprises the vertical board 7 shown as a single broad board having a top trimming member or board 8 overhanging more on the outer side than on the inside. Beneath the outer overhang of this board trimming member 8 there is disposed a cornice trimming including a strip 10 with a molding 11 which not only contributes decorative features to the outer side of the battlement unit but 55 acts as a reinforcement or stiffening means

extending longitudinally of the board 7. A base trimming member 12 projects as a slight overhang from the under side of the board 7, and further serves as a protection for the siding or sheeting of the side members 3 and the doors 4.

As a decorative stiffening just short of the ends of this front battlement unit, bracket members 13 at the ends of the cornice members 10 and 11, fit between the top 60 trimming member 8 and the base trimming member 12. There is accordingly produced a decorative feature on the outer side of this cornice with a minimum of material, which material has structural utility in 65 stiffening this battlement unit. Adjacent the base trimming member 12, and on the inner side of the board 7 there is provided the base member 14 firmly connected to the board 7 and coacting for stiffening the unit 70 upon the opposite side of the board 7 from the cornice members 10 and 11. Roof supporting means are provided as mounted on the inner side of the board 7 and resting upon the base 14, which supporting means 80 comprise the sustaining blocks 15 and the taller clamping blocks 16. Upon the sustaining blocks 15 may rest the inclined roof sustaining joists 17 clamped by bolts 18 to the member 16. These roof sustaining 85 members 17 may have bolted thereto cleats 19 on the under side of the boards 20 of the roof section units. These cleats 19 are assembled to the joists 17 by bolts 18.

The side battlement unit board 21 have 90 exterior finish means similar to the exterior finish means of the front battlement board 7. However, on the inner side, these side battlement units have, diagonally extending, a roof sustaining joist 22 parallel to 95 the intermediate joists 17 from the front battlement unit. These diagonally extending joists permanently attached to the boards 21 provide transverse and longitudinal stiffening for the side battlement 100 units and the cleats 19 on the roof sections may be bolted to this battlement carrying joist 22 as they are bolted to the intermediate joists 17 through the action of the bolts 18. Accordingly, these battlement 105 units have the single thickness boards 7, 21, as roof carrying structures with the decorative external stiffening and the roof carrying internal means also coacting as stiffening. However, this roof and these deco- 110

rative elements are apart from and all above the building sides. The roof is amply strong for normal usage and permits of ready erection of sectional buildings in an economical manner from unit bases. For instance, the units may be placed laterally of each other for building up into a structure of more extended capacity, say for garages to care for several machines, in 10 which instance the battlement between the units are omitted.

To facilitate the assembly of the members of the sections together for anchoring by the bolts 18, holes 23 may flare outward on 15 their sides toward each other so that the entering bolt may be directed or guided into bringing the parts into proper assembled relation. With the battlement units mounted on the sides and bolted together at the 20 corner, there is full stiffening in anchoring such units in position by the corner boards 24 extending from the corners of the side upward past the top plates of the sides and along the protruding portions of the means 25 7, 21, between the brackets 13 up to the under side of the top trimming member 8. This completes the mounting and trimming of the roof. The side sections 1, 2, may have 30 finish boards 25 covering the joints therebetween. There may be an additional intermediate transverse stiffening member or purlin 26 from the side plates 5 to support the joists 17. Sheet roofing material 27 may be placed in position over the boards 20 of 35 the sectional roof.

What is claimed and it is desired to secure by United States Letters Patent is:—

1. A battlement trimming for a roof embodying exterior finish board means, roof 40 carrying means mounted on and carried by one side of the board means, and a base supporting the board means as a unit with its roof carrying means.

2. A battlement trimming for an inclined 45 roof embodying an exterior finish board and roof carrying means mounted diagonally along and carried by one side of the board.

3. A battlement trimming for an inclined

50 roof embodying front board means from which the inclined roof may extend downwardly, a pair of parallel side board means one extending from each end of the front board means, said board means each having a base, which bases are assembled to approximate a plane below the incline of the 55 roof, and an inclined roof extending from the front board means and carried by the parallel side board means.

4. A battlement trimming unit for a roof comprising a board facing approximating 60 the battlement height, a top trimming board for the facing, cornice trimming on the outside of the means under the top trimming board longitudinally stiffening the board, a base trimming member for the board facing, 65 laterally of the base and trimming member an inwardly projecting carrying base, and adjacent the ends of the board facing exterior transversely extending decorative stiffening means for the board facing. 70

5. A battlement trimming unit for a roof comprising a board facing approximating the battlement height, a top trimming board for the facing, cornice trimming on the outside of the facing under the top trimming 75 board longitudinally stiffening the board, a base trimming member for the board facing, laterally of the base and trimming member an inwardly projecting carrying base, adjacent the ends of the board facing exterior transversely extending decorative stiffening means for the board facing, and interior roof carrying transverse stiffening means for the board facing. 80

6. A building having a pair of roof carrying plates extending from a corner, a pair of battlement roof carrying trimming units 85 extending from the corner and mounted on the plates, and a corner trimming for the building extending up from below the plates 90 to provide a corner trimming for the battlement units.

In witness whereof we affix our signatures.

CHAS. G. BRIGHAM.
WM. M. HAMILTON.
